(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The display screen or portion thereof with graphical user interface is shown in the accompanying drawing FIGURE. The broken line rectangle illustrates a display screen or portion thereof and forms no part of the claimed design.
